UNITED STATES PATENT OFFICE.

CHARLIE CASE, OF EMLENTON, PENNSYLVANIA.

AUTOMATIC SAFETY ATTACHMENT FOR STEAM-BOILERS.

SPECIFICATION forming part of Letters Patent No. 269,827, dated January 2, 1883.

Application filed August 2, 1882. (No model.)

To all whom it may concern:

Be it known that I, CHARLIE CASE, a citizen of the United States, residing at Emlenton, in the county of Venango and State of Pennsylvania, have invented a new and useful Automatic Safety Attachment for Steam-Boilers, of which the following is a specification.

My invention relates to improvements in safety attachments to steam-boilers, by which, when during the temporary absence of the engineer the water in the boiler may get low, by an automatic device the fire may be shut off from the boiler, and thereby prevent accident or explosion.

Figure 1 represents a boiler with my device attached thereto.

B is the boiler, and W the fire-box of the same, which may be constructed for the burning of gas, wood, coal, or oil.

Where gas is used for fuel, as it most generally is in the oil regions, O O represents a gas-tube running into the fire-box W, and through it the gas to be consumed is supplied.

P is a stop-cock, with a lever-handle, R.

C is the head of the boiler, with a gage-cock, G, attached to the boiler above the low-water line by the tube F.

V is a connection which supports the brass tube E. On the upper end of the tube E is a connection, X, supporting the steam-cock D and the arm Y.

H is a movable arm, bent downward from the tube E, and constructed so as to be adjusted at any position on the tube E, on which it slides, by the set-screw K. From the arm Y is a bent rod or spring, L, the lower end of which, when it is sprung in toward the tube E, catches into a hole, I, in the bent arm H.

S is a loose ring slipped on the bent arm H, 40 and kept thereon by the spring-rod L.

M is a rod that is hooked into the ring S; and, passing through a hole in the end of the stop-cock handle R, supports a weight, N.

The operation of my device is as follows: 45 The parts being all adjusted as shown in the drawings, the engineer goes away for a few moments, leaving the engine to "run alone." During his absence the water gets low in the boiler and sinks below the point where the 50 tube F is inserted. Then the steam passes up into the tube E, heating and expanding it, thereby lifting the connection X and arm Y. This lifts the end of the spring L out of the hole or catch at I in the arm H and permits 55 the ring S to slip off, and the weight N drops in the position shown by the dotted lines, and thereby closes the gas-cock P and puts out the fire.

In boilers where wood and coal are used as 60 a fuel the pipe O O can be connected with a tank of water, and the falling of the weight N would open the cock P and permit of a spray of water being thrown upon the fire to deaden it.

What I claim as my invention, and desire to secure by Letters Patent, is as follows:

The tube E, in combination with the arm Y, the spring L, the movable arm H, the ring S, the weight N, and the stop-cock P, constructed as described, for the purposes set forth.

CHARLIE CASE.
